US00D973709S

(12) **United States Design Patent** (10) Patent No.: **US D973,709 S**
(45) Date of Patent: **** Dec. 27, 2022**

(54) **VEHICLE DISPLAY SCREEN OR PORTION THEREOF WITH A GRAPHICAL USER INTERFACE**

(71) Applicant: **Toyota Research Institute, Inc.**, Los Altos, CA (US)

(72) Inventors: **Thor Lewis**, Sunnyvale, CA (US); **Ashlimarie Dong**, San Francisco, CA (US); **James Cazzoli**, Mahopac, NY (US); **Stephanie Paepcke**, Mountain View, CA (US); **Christoffer Rodemeyer**, New York, NY (US); **Jemma Robinson**, Brooklyn, NY (US); **Carlo Vega**, Brooklyn, NY (US); **David Landa**, Brooklyn, NY (US); **James Veluya**, Jersey City, NJ (US); **Helena Zhang**, Brooklyn, NY (US)

(73) Assignee: **Toyota Research Institute, Inc.**, Los Altos, CA (US)

(**) Term: **15 Years**

(21) Appl. No.: **29/757,715**

(22) Filed: **Nov. 9, 2020**

CLAIM

The ornamental design for a vehicle display screen or portion thereof with a graphical user interface, as shown and described.

DESCRIPTION

The FIGURE is a front view of a vehicle display screen or portion thereof with a graphical user interface showing our new design.

The broken lines in the FIGURE, showing the vehicle display screen and portions of the graphical user interface, are used to illustrate portions of the article; all broken lines form no part of the claimed design.
